DESIGN FOR A SHOE

Seymour Troy, New York, N. Y.

Application April 7, 1934, Serial No. 51,346

Term of patent 7 years

To all whom it may concern:

Be it known that I, SEYMOUR TROY, a citizen of the United States and a resident of New York, (Borough of Manhattan), in the county of New York and State of New York, have invented a new, original, and ornamental Design for Shoes, of which the following is a specification, reference being had to the accompanying drawing, forming part thereof.

I claim:

The ornamental design for a shoe, as shown.

SEYMOUR TROY.
